UNITED STATES PATENT OFFICE

GEORGE HAZELTON AND FRED RICKS, OF LEICESTER, ENGLAND, ASSIGNEES TO UNITED SHOE MACHINERY CORPORATION, OF PATERSON, NEW JERSEY, A CORPORATION OF NEW JERSEY

METHOD OF AND MACHINE FOR FITTING HEELS TO THE SOLES OF SHOES

Application filed March 23, 1929, Serial No. 349,443, and in Great Britain March 29, 1928.

This invention relates to methods of and machines for manufacturing shoes and is herein illustrated as embodied in a machine adapted to fit the heel-seat portions of shoes for the reception of Louis heels and to trim Louis heels for reception by the heel-seat portions of shoes.

A typical Louis heel has a lip extending transversely of the heel from one side of the heel to the other at the top portion of its breast, the front edge of the lip tapering substantially to a feather edge in order that the heel will blend properly with the shank portion of the shoe where it joins the latter.

In the manufacture of shoes having wooden Louis heels it is the practice to apply the heel, after it has been covered, to the sole of the shoe which sole already has been split at its rear portion to form a breast flap for covering the breast of the heel.

In fitting a Louis heel to a shoe the sole of the shoe is usually trimmed at its rear portion to form a reduced heel-seat portion for receiving the cupped attaching face of the heel and to form a pair of heel breast receiving shoulders extending laterally of the sole from the reduced heel-seat portion substantially at the heel-breast line of the sole.

In order to form a neat joint where the lip of the heel rests upon the shank portion of the sole, over which joint the breast flap of the sole should lie smoothly and without bulging, the heel breast receiving shoulders of the sole and the end portions of the feather edge of the heel breast should be of substantially the same size and complements of each other. Since the abutting ends of the feather edge as commonly made have no substantial surface areas the heel breast receiving shoulders which usually extend transversely of the sole are necessarily of small surface area and do not serve as satisfactory abutments against which to position the heel.

A shoe provided with a Louis heel and having a neat joint where the lip of the heel and the shank portion of the sole are joined but having surfaces or heel breast receiving shoulders of substantial area at the breast line of the sole is disclosed in application Serial No. 319,589, filed November 15, 1928, in

the name of Fred Ricks. The shoe of that application has a Louis heel having a projecting lip with a feather edge, at each end of which is a shoulder having a substantial surface area positioned at a substantial angle to the feather edge. These shoulders are constructed and arranged to abut against the corresponding heel breast receiving shoulders formed upon the sole of the shoe.

An object of this invention is to provide a machine for trimming a Louis heel having a projecting lip with a feather edge to form shoulders of substantial surface areas at the ends of the feather edge.

Another object of this invention is to provide a machine for trimming a Louis heel and the sole of a shoe in such a manner that the trimmed heel will have portions formed thereon which are complementary to portions formed upon the sole in order to facilitate the accurate positioning of the heel upon the sole for registry therewith.

With the above-stated objects in view and in accordance with a feature of the invention, the illustrated machine comprises a novel heel-seat fitting and heel trimming machine having, in combination, means for trimming a heel, and means for operating upon the sole of a shoe to trim the heel-seat portion thereof to a size determined by the heel.

In order that the heel and the sole of the shoe may be positioned in correlated positions in the machine so that when trimmed they will correctly mate with one another, the illustrated machine is provided with members for receiving the sole of a shoe, members for receiving a heel, and mechanism controlled by the heel for determining the position of the sole in the sole receiving means.

To position the heel correctly in the machine while it is being trimmed, and in accordance with another feature of the invention, the illustrated machine is provided with means for positioning the heel in the machine widthwise of the heel before it is positioned lengthwise of the heel, and means for normally urging the positioning means into contact with the heel and for locking the positioning means against movement away from the heel.

A further feature of the present invention comprises novel means for trimming a Louis heel having a protruding portion terminating in a feather edge, which heel has been positioned in the machine as above described. For this purpose the illustrated machine is provided with a pair of knives having a definite arrangement relatively to the heel positioning means and mounted for movement laterally and forwardly of the heel for forming shoulders of substantial surface areas at the ends of the feather edge at a substantial angle to the feather edge.

In its method aspect, as herein exemplified the invention is practiced by positioning a sole to be operated upon in correlated arrangement with the heel, and trimming the heel to form sole-engaging shoulders and the sole to form heel-breast receiving shoulders while the heel and sole are in their correlated positions, which heel-breast receiving shoulders are substantially complementary to the shoulders formed upon the heel to insure the proper positioning of the heel upon the sole of the shoe.

A heel-seat fitting machine comprising certain features which are similar to those portions of applicants' heel-seat fitting machine which are utilized in operating on the shoe sole is disclosed and claimed in an application of Gouldbourn, Ricks and Barclay, Serial No. 307,937, filed September 24, 1928.

A machine embodying the invention and by the aid of which the method of the invention may be advantageously practiced will now be described with reference to the drawings, in which:

Fig. 1 is a perspective view of the heel-seat portion of a shoe fitted in the heel-seat fitting and heel trimming machine embodied in the present invention, the breast flap of the shoe being shown turned back from the heel-seat;

Fig. 2 is a side elevation of the rear portion of a completed shoe which has had its heel fitted to its sole in the machine embodied in the present invention and illustrating the appearance, after the heel has been incorporated in the shoe, of the side edges of the joint formed between the sole and the heel of the shoe;

Fig. 3 is a perspective view of a heel trimmed in the machine embodied in the present invention and arranged to fit the heel-seats shown in Figs. 1 and 5;

Fig. 4 is a plan view of the rear portion of a sole of a shoe which has had its heel-seat partially trimmed in another machine prior to the application of the sole to a shoe and prior to the heel-seat fitting operation performed by the illustrated machine;

Fig. 5 is a perspective view of the heel-seat portion of a shoe formed by the illustrated machine and showing a completed heel-seat

which has been formed upon a sole similar to the sole shown in Fig. 4;

Fig. 6 is a side elevational view of a heel-seat fitting and heel trimming machine embodying the invention, some parts being shown in section more clearly to bring out the construction thereof;

Fig. 7 is a plan view of the machine with parts broken away to show the interior structure thereof;

Fig. 8 is a front view of the machine with parts shown in section;

Fig. 9 is a detail sectional view of a portion of the machine, showing a shoe in position therein having its sole trimmed to form a reduced heel-seat portion of the heel;

Fig. 10 is a perspective view of the rear portion of a shoe during the performance of the heel-seat fitting operation, showing the position of crease plates of the machine and beveling knives for trimming the marginal portions of the heel-seat portion of the sole lengthwise of the sole;

Fig. 11 is a sectional view taken on the line XI-XI of Fig. 9;

Fig. 12 is a perspective view showing in detail the construction of the sole beveling knives and actuating mechanism therefor and also illustrating mechanism for actuating heel trimming means;

Fig. 13 is a front view partly in section of a portion of the mechanism for positioning and locking a back gage and a heel clamping means; and

Fig. 14 is a side elevational view of the mechanism shown in Fig. 13 with parts broken away to show the interior construction thereof.

The illustrated machine, which will later be described in detail, comprises a support for holding a shoe the sole of which is to be trimmed to form a reduced heel-seat portion and a pair of heel-breast receiving shoulders thereon, mechanism for arranging the shoe in the machine for carrying out the trimming operation, a pair of knives for beveling the sole to form the reduced heel-seat portion of the sole, a pair of knives for forming the heel-breast receiving shoulders upon the sole, mechanism for truncating portions of the lip of the heel to form shoulders thereon, and mechanism for locating the heel and the sole in correlated position in the machine to insure that the shoulders formed upon the heel and the heel-breast receiving shoulders are complementary to one another and are arranged to register or mate with one another to facilitate the correct positioning of the heel upon the sole of the shoe.

For purposes of illustration, it will be assumed that the shoe being operated upon in applicants' machine is of the well-known McKay type and has a reduced heel-seat portion 30 constructed to receive the cupped attaching face of a Louis heel 34 which is cov-

ered with celluloid, leather or a textile material on its sides 36 and has a covering folded over its top-lift receiving face 38, its breast 40 and its attaching face. As is customary in Louis heels, the upper portion of the breast of the heel projects forwardly as it approaches the attaching face, forming a lip portion 42 having, as viewed from the sides of the heel, a somewhat wedge shape. The forward part of the lip is thinned to a feather edge 44 which extends from one side of the heel to the other and which is adapted to conform to the surface of the shank portion 46 of the sole 48 of the shoe. As is usual in shoes having Louis heels, the sole is split to provide a breast flap 50 which is applied to the breast of the heel.

In the fitting of a Louis heel to a sole it is necessary that the feather edge 44 of the lip portion 42 shall fit snugly upon the median portion of the sole of the shoe, in order that the breast flap 50, which is applied to the breast of a heel, shall blend properly with the sole where it lies over the feather edge 44 of the heel. If for any reason the feather edge does not seat properly upon the sole, there will be a bulge in the surface of the sole at the portion indicated at 52 (Fig. 2) where the feather edge 44 meets the shank portion of the sole, which bulge spoils the appearance of the shoe.

The heel 34 is trimmed in applicants' machine by truncating its corners 54 which are formed between the breast edges 56, the feather edge 44 and the rim portion 58 of the attaching face to form the surfaces or shoulders 60 which are constructed and arranged to engage complementary heel breast receiving shoulders 62 formed on the sole of the shoe, which heel breast receiving shoulders are preferably undercut heightwise of the sole, as indicated by reference character 64, and extend from the reduced heel-seat portion 30 of the sole substantially at the heel breast line 66 rearwardly and laterally of the shoe.

The shoes shown in Figs. 1 and 5 have their sole attaching stitching 68 extending along the shank portion 46 of the shoe to points somewhat rearward of the breast line 66 of the sole. The heel-seats which are formed by applicants' machine are of full thickness throughout a substantial portion of their width and include steeply beveled portions 70 extending along their margins in a direction substantially lengthwise of the shoe. By utilizing a wide reduced heel-seat portion 30 of a sole having steep bevels 70, it is possible to produce a shoe having a sole with its line of stitching 68 uncut rearwardly of the breast line 66, which results in an improved heel-seat.

The sole 48 of Fig. 1 is what is termed a "short sole", and accordingly its rear end 74 does not require trimming. This sole has been trimmed along its marginal portions

72 lengthwise of the shoe in applicants' machine to form the beveled portions 70. The sole shown in Fig. 5 has been given a preliminary heel-seat trimming in another machine prior to its attachment to the shoe, as shown in Fig. 4, along its rear portion 76 as well as its rear side portions 78 to form a tapered tongue portion 80 (Fig. 5) extending from the lines 82 rearwardly of the sole, the two soles being alike from the lines 82 forwardly of the sole.

The breast of the heel illustrated in Fig. 3 is provided with a forwardly extending projection adjacent to the attaching face of the heel. This projection is provided with a feather edge 44 extending over a portion of the width of the heel and shoulders 60, forming a substantial angle with the feather edge at the ends 84 of the feather edge and extending rearwardly of the heel as well as toward the sides 36 of the heel, said shoulders 60 also extending forward of the heel as they approach the attaching face of the heel.

The shoulders 60 may be said to be formed by a pair of substantially plane surfaces each defined by two lines 86 and 88 intersecting at points 90 on the breast edge of the heel, the line 86 extending forwardly of the heel and toward the center of the feather edge 44 from the point 90 and the other line 88 extending forwardly of the heel and toward the heel attaching face, said planes truncating the corners 54 of the heel.

The heel breast receiving shoulders 62 of the sole of the shoe extend laterally and rearwardly of the sole from the marginal portions 70 of the reduced heel-seat portion of the sole, said shoulders beginning at the points 92 substantially at the breast line 66 of the sole and being undercut at 64 (Figs. 1, 2 and 5). The breast receiving shoulders 62 may be said to be formed by a pair of substantially plane surfaces each defined by two lines 61, 63 (Figs. 1 and 5) intersecting at a point 65 on the tread surface of the sole rearwardly of the breast line 66 of the sole and at the lateral edge of the sole, one of the lines extending forwardly of the sole and toward the center of the breast line 66 of the sole and the other line extending forwardly of the sole and toward the attaching face of the sole.

The heel thus formed is adapted to be received by the heel-seat portion of the shoe so that the heel-seat lies snugly in the cupped attaching face of the heel, the shoulders 60 abutting against and mating with the heel breast receiving shoulders 62 and the feather edge 44 resting upon the median portion 46 of the sole at the breast line 66. Such an arrangement of parts produces a shoe having at the meeting of the heel-seat and the base of the flap a union of parts that is smooth and graduated and gives a neat finish to the shoe.

The machine as a whole includes three principal groups of instrumentalities carried by a lower head 102 (Figs. 6 and 8), a middle head 104 and a top head 106, respectively. The lower head 102 carries the shoe supporting means and forms a base for the middle head 104 and the top head 106. The middle head 104 carries the sole trimming mechanism and the actuating mechanism therefor while the top head 106 carries the heel clamping means for positioning and locking the heel in the machine.

The lower head 102 carries a forwardly extending horizontal bracket 108 having a T-shaped horizontal guideway 110 extending forwardly and rearwardly of the machine. Slidably mounted in the guideway 110 is a work support 112 (Fig. 6) having a T-shaped base 114 (Fig. 8) slidably mounted in the guideway 110 so that a shoe mounted thereon may be moved into and out of position to be trimmed. The work support also comprises a vertically extending portion 116 bored as shown at 118 to receive a post 120 having a slot 122 extending in the direction of its length and containing a pin 124 which is supported by the vertically extending portion 116 of the work support. The upper end of the post 120 is provided with a threaded recess 126 which receives the threaded shank portion 128 of a shoe supporting plate 130 (Figs. 6 and 9) fixed in adjusted position relatively to the post 120 by a nut 132 upon the shank portion of the shoe supporting plate 130. A spring 134 is located within the recess 126 of the post 120, the ends of which spring engage against the pin 124 and the lower end 136 of the shank portion 128 of the shoe supporting plate 130, normally to hold the post 120 in the raised position shown in Fig. 6.

As will later be brought out, when the sole of the shoe is being trimmed the post 120 is in lowered position relatively to the vertically extending portion 116 of the work support, as shown in Fig. 9. In order to raise the post 120 for fixedly positioning the shoe to be trimmed, an arm 138 (Figs. 6 and 9) pivoted for movement about a pin 140 mounted in the forwardly extending horizontal bracket 108 is raised upwardly through a slot 142 (Fig. 7) in the bracket 108 and a slot 144 in the work support 112 into contact with the lower end 146 of the post 120. The forward end of the arm 138 is normally held down by a heavy spring 148 which is connected to the arm at its forward portion 150. Pivoted about the pin 140 is also a forwardly extending dog 152 which is carried with but movable relatively to the arm 138 by a spring 154, the dog being arranged to engage a rack 156 at the under part of the work support 112 to hold the work support from sliding forwardly of the machine when the shoe is having its heel-seat fitted.

The rear portion 158 (Fig. 6) of the arm

138 is connected by a link 160 to one end of a floating lever 162 the other end of which is pivoted to a plunger 164 which through associated mechanism hereinafter described operates a pair of crease plates 166 arranged to enter the rand crease of the shoe as far as the line of stitching 68 between the shoe upper and the sole. The floating lever 162 is connected at its central portion to a rod 168 (Fig. 6) extending downwardly to a treadle 172.

The middle head 104 is provided with bearings one of which is shown at 174 (Figs. 6 and 8) for supporting a forwardly and rearwardly extending driving shaft 176. A cam 178 having cam grooves 180, 182 is mounted upon the shaft 176 to actuate through other mechanism, later to be described, beveling knives 184 which are moved lengthwise of the sole to form the portions 70 of the heel-seat portion of the sole, sole shoulder knives 186 which are moved transversely and forwardly of the sole to form the heel breast receiving shoulders 62, and heel shouldering knives 187 (Figs. 7 and 8) which form the shoulders 60 upon the Louis heel above described.

The middle head 104 has on each side thereof and extending laterally therefrom a pair of brackets 188 (Fig. 7) spaced from one another, each pair providing a guideway 190 extending parallel to the front of the machine and slidably supporting and guiding two laterally movable sliding beds 192, the guideways on opposite sides of the machine being in the same horizontal plane and in line with one another.

Since the sliding beds 192 with their associated parts are the same on both sides of the machine, it will be necessary to describe but one side, it being understood that the parts described are duplicated upon the opposite side of the machine. Each of the sliding beds 192 carries one of the sole shoulder knives 186, one of the beveling knives 184 and one of the crease plates 166, and upon the under side of each of said sliding beds there is a boss 194 (Fig. 8) in which is fixed a depending stub 196, the lower end of which is pivoted at 198 to the outer end of a link 200, the other end of the link being connected at 202 to the plunger 164 which is mounted for vertical movement in a bearing 204 in the lower head 102 of the machine. The lower end of the plunger 164 (Fig. 6) is connected to the floating lever 162 already described, the mechanism being constructed and arranged so that downward pull on the plunger rod will move the sliding beds 192 toward one another in the guideways 190 in the middle head 104 of the machine.

The lower end of the plunger rod 164 (Fig. 6) has a lug 206 extending forwardly therefrom, which lug is provided with a hook 208 for receiving the end of a spring 210 the other end of which spring is connected to the lower

head 102, the spring serving to keep the plunger rod 164 in a raised position which results in normally holding the sliding beds 192 at their extreme positions away from one another in the guideways 190.

The illustrated machine is also provided with a holdown clamp 212 which serves to engage the attaching face of the sole of the shoe between the beveling knives 184 (Fig. 10) while the sole is being trimmed in order to assist in tightly securing the sole against movement during the trimming operation. The holdown clamp is pivoted at 214 (Fig. 6) to the top head 106 through an arm 216 which is connected near its central portion 218 to a downwardly extending clamp actuating rod 220 passing through the forwardly extending lug 206 on the plunger rod 164. The clamp actuating rod 220 is provided with a pair of collars 222, 224 the former of which serves to confine a spring 226 between itself and the forwardly extending lug 206 and the latter of which is arranged to be engaged by the lug 206 when the plunger rod is lowered. As the plunger rod 164 is lowered to draw the sliding beds 192 and their crease plates 166 together it will depress the rod 220 and cause the holdown clamp 212 to engage the tread surface of the sole of a shoe as shown in Fig. 9. A turn buckle 228 upon the rod 220 may be used for varying the amount of pressure with which the clamp will engage the sole of the shoe and the time at which such engagement will occur.

45 The crease plates 166, which are located at the forward inner corners of the sliding beds 192 and which assist in maintaining the sole in position to be trimmed just above their level (Fig. 9), are strong enough to resist the upward pressure of the work support post 120 and include thin finger portions 230 (Fig. 12) constructed and arranged to enter between the shoe upper and the sole at the sides of the heel-seat portion of the shoe.

46 The upper surfaces of the crease plates 166 are provided with knife guideways 232 (Figs. 7 and 12) for receiving the beveling knives 184, said guideways being formed by the shoulders 234 extending lengthwise of the plates and the flat surface portions 236 (Figs. 8, 10 and 12) which also extend lengthwise of the plates. The beveling knives 184 are arranged to move in the guideways 232 along the angled portions of the crease plates formed by the shoulders 234 and the flat surface portions 236. The sliding beds 192 may be attached to the crease plates in any convenient manner such as that shown in Figs. 8 and 12 in which each plate includes a tongue portion 240 and two threaded bolts 242 which may be fastened to the inner side 244 (Fig. 8) of the sliding beds 192.

47 Each sliding bed 192 is provided near its front margin with a guideway 246 (Fig. 7) which extends laterally and forwardly of the

machine, the inner end of the guideway adjacent to the crease plates 166 being forward of the machine relative to the outer end of the guideway. A knife carrier slide 248 is mounted for reciprocation in each guideway 246 and has fixed to it a downwardly extending rod 249 (Fig. 8) which is adjustable lengthwise of the slide in a slot 250 (Fig. 7) by means of a nut 252 threaded upon the upper portion of the rod 249 so that the slide 248 may be initially adjusted in its guideway 246, the downwardly extending rod 249 retaining a fixed position with respect to the knife carrier slide 248 during the operation of the machine.

48 The lower portion of each downwardly extending rod 249 passes through a bifurcated portion 256 (Fig. 7) of an arm 258 having a sleeve portion 260 (Fig. 8) mounted for turning movement upon the depending stub shaft 196 attached to the sliding bed 192. Mounted on each sleeve portion 260 is another arm 262 extending laterally of the machine, the end of which is pivoted to a link 264 (Fig. 8) extending rearwardly of the machine and pivoted to a cross-head 266 (Fig. 6) which is attached to a slider 268 constructed and arranged to slide forwardly and rearwardly of the machine in a guideway 270 (Figs. 6 and 8) in the frame of the machine, the slider 268 carrying an upwardly extending roller 272 positioned in the groove 180 of the cam 178.

49 It will be clear that as the cam 178 is rotated and the cross-head 266 is moved forwardly and rearwardly of the machine the knife carrier slides 248 will be moved laterally and forwardly of the machine on the sliding beds 192. Since the connecting links 264 are of considerable length, movement 100 of the sliding beds toward and away from one another does not affect, to any harmful extent, the positions of the knife carrier slides 248 relatively to the sliding beds 192.

50 The knife carrier slides 248 are each provided with an upwardly extending lug 274 having a cylindrical recess 276 (Fig. 8) with its axis parallel with the direction of movement of the knife carrying slides 248. A knife carrier 278 has a cylindrical shank portion 280 received by the cylindrical recessed portion 276 of each upwardly extending lug 274 and is held in place therein by a bolt 282 (Figs. 7 and 8) passing through the cylindrical bored portion. The knife carrier 278 is also provided with a portion 284 extending forwardly and downwardly of the machine and provided with a T-shaped groove 286 (Fig. 7) for receiving the thin flat knife 186 and a clamping plate 290, T-shaped in cross-section, which plate is inserted in the T-shaped groove forward of the knife 186, the knife being held in position in the knife carrier by a screw 292 130

(Figs. 7 and 11) passing through the T-shaped clamping plate 290, the knife 186 and entering the rear face 294 of the forwardly extending portion of the knife carrier so that the thin flat knife may be clamped between the bottom of the groove 286 and the clamping plate 290.

The construction and arrangement of the parts above described is such that in operative position (Figs. 6 and 7) the knife 186 extends downwardly and forwardly of the machine at a steep inclination to the horizontal, the plane in which the blade lies being parallel with the line of movement of the knife carrier slide 248. With such an arrangement of parts it is thus clear that the heel breast receiving shoulders 62 formed at the forward portion of the heel-seat will extend laterally and rearwardly of the sole 20 and have an undercut 64 widthwise of the sole.

The lower cutting edge 296 (Fig. 11) of the shouldering knives 186 are arranged at right angles to the sides of their respective knives 25 and are higher at their inner corners than at their outer corners in order to form an angle with and transversely of the attaching face of the sole.

Each of the cutting edges 296 (Fig. 11) of the shouldering knives 186 is arranged substantially at the same inclination to the attaching face of the sole transversely of the sole as the cutting edge of its corresponding beveling knife 184 so as to form a clean-cut shoulder at 91 (Figs. 1 and 5), the shouldering and beveling knives being arranged so as not to appreciably cross the paths of one another.

Each of the shouldering knives 186 (Fig. 40) moves along the front edge 304 (Fig. 7) of the crease plate 166, which front edge is parallel to the line of the movement of the knife carrier slide 248, the knife thus being supported against rearward springing by the crease plate and forming a shearing couple therewith.

In order to support and guide the beveling knives 184, each of the sliding beds 192 has a raised portion 306 (Fig. 8) the under side 50 of which has a horizontal dovetail guideway 308 which extends forwardly and rearwardly of the machine and in which a knife carrier 310 (Figs. 8 and 12) is mounted for movement. The upper surfaces at the rear ends of the knife carriers 310 (Figs. 6, 7 and 12) are provided with transverse slots 312 for receiving a cross-head 314 which is constructed and arranged simultaneously to actuate both knives and to allow the knife carriers 310 to be moved toward and away from one another with the sliding beds 192, without causing any relative movement in a direction lengthwise of the knife carriers 310 between the sliding beds 192 and the knife carriers.

The cross-head 314 is integral with a dovetail slider 316 which is arranged to slide forwardly and rearwardly of the machine in a horizontal slideway 320 (Fig. 6) formed in the bottom portion of the top head 106, the dovetail slider 316 carrying a depending cam roll 318 that engages the cam groove 182 in the cam 178. Upon rotation of the cam 178 the dovetail slider 316, through the cross-head 314, moves the knife carriers 310 forwardly and rearwardly of the machine to bevel the marginal portions of the heel portion of the sole in a direction extending substantially lengthwise of the shoe.

The under surface of each knife carrier 310, along its inner margin 322 (Fig. 12), is beveled to slope upwardly and toward the longitudinal axis of the machine at a steep angle to a horizontal plane. The knife 184 having an elongated portion with a beveled cutting edge 324 and a flanged portion 328 is fixed to the front face 326 of the knife carrier 310 by means of the flange 328 which is screwed against the said front face 326 of the knife carrier, the knife thus extending forwardly of the knife carrier and having its beveled edge 324 extending laterally of and forming a substantial angle with the flat surface portions 236 of the crease plates and the attaching face of the sole. It will be noted that the angle which the cutting edge of the knife makes with the surface of the sole may be changed as desired, such change being brought about by attaching knives of different angles to the knife carrying slides.

Since the knives 184 travel in the knife guideways 232 with their cutting edges 324 inclined at an angle to the crease plates 166, and their corners 330 moving along the shoulders of the crease plates (Fig. 12), it will be clear that the finger portions 230 of the crease plates 166 will extend far enough between the sole of the shoe and the shoe upper to protect the upper from being cut by the knives, and the knives will be prevented from springing relatively to the plate as they trim the lateral marginal portions of the sole.

The shaft for rotating the cam 178 is actuated by a one-revolution clutch 332 mounted at the rear of the machine and is thrown into operation by the hand lever 334 (Fig. 8).

In order to position the shoe lengthwise in the machine so that the beveling knives and the shouldering knives will operate at correct positions on the sole to form a reduced heel-seat portion of such length that the heel-breast receiving shoulders 62 which are the complements of the heel shoulders 60 will register with the heel shoulders correctly to position the heel upon the sole of the shoe, mechanism is provided whereby rearward movement of the shoe to be operated upon is halted by contact of the rear portion of the shoe upper against a back gage 382 (Fig. 6) having a concaved front face 384, the position of the

back gage being determined by a heel clamp or heel-clamping mechanism 385 constructed and arranged to receive the heel to be trimmed heel-attaching face down and heel breast toward the front of the machine as shown in Figs. 6 and 8. The back gage 382 is slideable forwardly and rearwardly of the machine in a guideway 388 (Fig. 6) in the middle head 104.

10 The top head 106 carries the heel clamp and connecting mechanism for regulating the position of the back gage 382. The back gage 382 has rigidly fixed thereto an upwardly extending post 390 (Fig. 6) having its upper 15 end connected to a traveler 392 which slides forwardly and rearwardly of the machine in a guideway 394. An upstanding post 396 is connected to the traveler 392 and is provided with a threaded hole 398 extending parallel 20 to the length of the slider and receiving a screw 400 having a knurled head 402 at its rear end. The front end of the screw 400 is provided with a collar 404 that lies in a recess 406 (Fig. 7) in the rear gage plate or abutment 408 which has a curved recessed portion 410 (Figs. 6 and 7) for engaging the rear marginal rim portion of the heel.

25 The front portion of the top head 106 carries a breast gage or abutment 412 arranged to engage the feather edge 44 of the projecting lip 42 of the heel (Fig. 6), the gage being mounted for movement forwardly and rearwardly of the machine in a guideway 416 (Fig. 7) for initial adjustment of the 30 gage to accommodate different sizes and shapes of heels. The initial adjustment of the gage is effected by means of a screw 418 (Fig. 6) which passes through an upstanding threaded recess in a flanged portion of the 35 breast gage, the screw being mounted for rotation in the lug 422 of the top head.

The top head 106 is also provided (Fig. 7) with a pair of horizontal guideways 426 (Fig. 7) extending toward the longitudinal center of the machine and forwardly of the machine. In order to engage the sides of the heel for centering the same in the machine, clamp slides 430 are arranged for reciprocation in the guideways 426, each clamp slide 40 carrying clamping members 432 connected to the clamp slides 430 by screws. The heel contacting ends of the clamps 432 (Fig. 8) are inclined upwardly and toward one another at an angle of about 75 degrees to the horizontal and preferably carry clamp pieces 438 of rubber or leather in order that they will not damage the covering on the heel.

Projecting downwardly from the clamp slides 430 are pivot pins 440 connected by 45 links 442 to other pivot pins 444 (Figs. 6 and 7) that project upwardly from a heel clamp actuator 446 (Fig. 6), the arrangement and positions of the parts being such that when the clamp slides 430 are in their outermost position the links 442 will appear as a

straightened toggle and when the clamp slides are in their innermost position the links appear as a broken toggle as shown in Fig. 7.

The under surface of the rear gage plate 408 (Fig. 6) and the upper surface of the heel clamp actuator 446 are provided with racks 448, 450 respectively, which engage a pinion 452 carried by a compensating block 454, slideable in the guideway 456 in the top head 106 of the machine. The compensating block 454 is operated by a pin 458 (Figs. 6 and 7) extending from one side thereof, the pin being received by a bifurcated portion 460 of an upwardly extending arm (Fig. 7) which is fixed upon a rock shaft 464, mounted for rotation in a bearing 465 supported by the middle head 104.

The clamping members 432 are mounted for movement with the back gage or abutment 408 through the pinion 452 carried by the compensating block 454 and are arranged to engage the heel laterally to position the heel widthwise of the heel in the machine before the heel is positioned lengthwise of the heel in the machine. When the heel is substantially in its proper lateral position to be trimmed in the heel clamp the back gage or abutment 408 is arranged to engage the heel to move the same to its proper position lengthwise of the heel to be trimmed.

Clamping of the heel in this manner thus not only positions the heel to be operated upon by the heel-trimming means, which will be described later, but also automatically positions the back gage 382 so that the sole of the shoe will be properly positioned lengthwise of the shoe in the machine to have its heel-seat and heel breast receiving shoulders arranged to facilitate the correct positioning of the heel upon the sole.

Provision is also made for normally urging the heel clamp in contact with the heel and for urging the back gage forwardly of the machine. Means is also provided for locking the back gage against rearward movement under pressure of the shoe, the locking means being constructed and arranged to hold the back gage in its foremost position against the shoe upper and to hold the heel clamp against the heel.

Keyed to the outer end of the rock shaft 464 is a hub 466 (Fig. 13) carrying an upright arm 468 having a yoke portion 470 (Figs. 13 and 14) in which is mounted a pawl pin 472. Extending axially from the hub 466 are a pair of projecting lugs 474 which are arranged to be engaged by a pair of axially extending lugs 476 upon a lever 478 loosely mounted upon the rock shaft 464. A treadle rod 480 is pivoted to the lever 478 and forwardly extending from said lever 478 is an arm 482 carrying a spring 484 for holding the arm 482 normally in a downward position. Clockwise movement of the arm 482 through mechanism carried by the yoke 470,

which mechanism will be later described, causes the upright arm 468 to move in a clockwise direction (Fig. 14), thereby moving the compensating block 454 forwardly of the machine. Conversely upon depressing the treadle rod 480 the lugs 476 abut against the lugs 474 rotating the upright arm 468 in a counterclockwise direction thereby moving the compensating block 454 rearwardly of the machine. 5 The compensating block carrying with it the pinion 452 which engages the rear gage plate or abutment 408 and the heel clamp actuator 446 to move these two parts rearwardly of the machine. Rearward movement 10 of the heel clamp actuator 446 causes the clamps 432 to move away from one another by reason of the toggle action of the links 442. The heel clamp is thus opened to permit a new heel to be inserted, which heel 15 is placed with its attaching face downwardly upon the top surface 486 of the heel supporting plate (Fig. 6) and with its breast 40 resting against the breast gage or abutment 412. Upon the release of the treadle rod 480 the 20 spring 484 through the upright arm 468 and mechanism carried thereby, which will later be described, causes the compensating block 454 to move forwardly of the machine carrying with it the rear gage plate or abutment 25 408 and heel clamp actuator 446. Should the clamps 432 come to a stop after laterally positioning the heel to be trimmed before the rear gage plate 408 has completed its function of lengthwise positioning of the heel in 30 the heel clamp, the compensating block 454 will continue to move forwardly, the pinion 452 rolling upon the ratchet teeth 450 of the heel clamp actuator and urging the rear gage plate 408 forwardly of the machine until it 35 has positioned the heel to be trimmed lengthwise of the heel, at which time forward movement of the compensating block ceases, the heel being held in position by the treadle spring 484. 40

45 A convenient form of locking mechanism for the heel clamp and the back gage 382 embodies a device which locks the back gage against movement rearwardly of the machine as well as locks the heel clamp for holding 50 the heel securely in position to be trimmed. The locking mechanism comprises a ratchet disk 490 mounted on the frame of the machine and engaged by a depending pawl 492 mounted upon an eccentric sleeve 494 55 carried by the pawl pin 472 and provided with a pawl spring 496 (Fig. 14) fastened in the yoke 470 for urging the pawl into engagement with the ratchet disk 490. The eccentric sleeve 494 has a laterally depending 60 arm which will be referred to as the eccentric actuator 498 and projecting forwardly of the machine from the eccentric actuator is an arm 500 connected by a spring 502 to the arm 482, the arrangement of parts being such 65 that the eccentric actuator 498 is normally in

a substantially upright position (Fig. 14) during the trimming operation of the machine.

The lever 478 which is free to rock on the shaft 464 and carries projecting lugs 476 arranged to engage the lugs 474 of the hub 466 is provided with an upstanding ear 504 which is arranged to engage a laterally extending portion 506 of the pawl 492 so as to rock the pawl in a clockwise direction to raise the pawl 492 from the ratchet disk 490 prior to the time that the lugs 476 of the lever 478 engage the lugs 474 of the hub 466. Upon depression of the treadle rod 480 the upstanding ear 504 moves in a counterclockwise direction, as viewed in Fig. 14, and lifts the pawl 492 from engagement with the ratchet disk 490. Upon further depression of the treadle rod, the lugs 476 on the lever 478 engage the lugs 474 of the hub 466 and rock the upright arm 468 in a counterclockwise direction (Fig. 14) carrying with it the rock shaft 464 which moves the compensating block 454 rearwardly of the machine, thereby moving the back gage rearwardly of the machine and opening the heel clamp for the removal of the heel. A new heel is then inserted in the heel clamp and the pressure of the treadle is released allowing the spring 484 to move the lever 478 in a clockwise direction. As the lever moves in a clockwise direction, its upstanding ear 504 engages the eccentric actuator 498 to throw the pawl 492 against the ratchet disk 490 and to rock the upstanding arm 468 in a clockwise direction (Fig. 14). Since the upstanding arm 468 is actuated in a clockwise direction through contact of the upstanding ear 504 of the lever 478 with the eccentric actuator 498, the pawl 492 will at all times be pressed down upon the ratchet disk to prevent backlash, the parts of the mechanism thus being held against backward movement.

The heel trimming mechanism for operating upon a Louis heel to form shoulders 60 which are complements of and are constructed and arranged to register with the heel breast receiving shoulders 62 will next be described. The top head 106 at its upper surface is provided with a pair of horizontal guideways 510 (Fig. 7) extending laterally and slightly forwardly of the machine and parallel with the guideways 246 of the sole shouldering knives 186. A knife carrier slide 512 is positioned for rectilinear movement in each of the guideways 510 and has one of the heel shouldering knives 187 mounted upon its forward end 514 (Fig. 8) by means of a clamping plate 516 and screw 518 such as are used in securing the sole shouldering knives 186 to their knife carriers.

The cutting edge 520 of the knife 187 as observed from the front of the machine (Fig. 8) lies in a vertical plane and as viewed from the side of the machine (Fig. 6) lies in a

plane extending upwardly and rearwardly of the machine from the surface of a heel supporting plate 522 at a suitable angle for forming the shoulders 60 on the heel. The heel supporting plate 522 is provided with a shoulder 524 (Figs. 6, 7 and 8) at its forward portion along which shoulder the knife 187 is arranged to move in order to support the knife against rearward springing.

10 Each of the knife carrier slides 512 is reciprocated through a rod 526 (Fig. 8) passing through the slide and extending downwardly therefrom, which rod may be clamped to the carrier slide when it has been positioned and adjusted as outlined in connection with the knife carrying slides 248.

15 The lower portion of the rod 526 (Fig. 7) is embraced by a bifurcated portion 528 of the arm 530 extending forwardly and rearwardly of the machine and pivotally mounted upon the pin 532 carried by the top head 106. An inwardly extending arm 531 rigidly connected to the arm 530 has its rear end pivoted to the front end of a forwardly and 20 rearwardly extending link 534 (Figs. 7 and 12) the rear end of which is pivoted at 536 (Fig. 12) to the laterally extending cross head 314 which has been described. The heel shouldering knives 187 at opposite sides of 25 the machine will form shoulders on the heel simultaneously since they are both connected to the cross head 314.

30 In carrying out the heel-seat fitting and heel trimming operation the operator depresses the treadle rod 480 to open the heel clamp and places a covered heel in said heel clamp with the attaching surface of the heel against the heel supporting plate 522 and the breast of the heel engaging the breast gage 35 or abutment 412 which has been initially adjusted. The treadle rod 480 is then released whereupon the clamps 432 move inwardly from the sides of the heel and the rear gage plate 408 moves forwardly of the machine to 40 position the heel in the machine and to lock the heel thereon, the back gage at the same time being automatically moved forwardly of the machine for positioning the sole attached to the shoe upper in the machine 45 lengthwise of the shoe.

50 The operator next places the inverted shoe upon the shoe supporting plate 130 with its heel end toward the machine and slides the work support 112 rearwardly until the rear 55 end of the shoe engages with and is stopped by the back gage 382, the shoe supporting plate 130 being depressed by hand against the pressure of spring 136 as the support is slid rearwardly so that the thin finger portions 230 of the crease plates 166 may enter the crease between the shoe upper and the sole.

60 The treadle 172 is then depressed causing the sliding beds 192 to be moved toward one another and causing the crease plates 166 fur-

ther to enter the crease between the shoe upper and the sole. As the treadle 172 is still further depressed the post 120 is moved upwardly and as the treadle 172 comes near the bottom of its stroke the hold-down clamp 212 is brought into operative position upon the attaching face of the sole of the shoe (Fig. 9), the crease plates continuing to enter between the shoe upper and the sole until they are stopped by the line of stitching 68. During 70 the heel-seat fitting operation the treadle 172 is kept depressed to hold the parts in their relative positions, the sole being substantially flat with its marginal portions undistorted by the entrance of the crease plates. 75

80 When the shoe has thus been placed in operating position the operator next depresses the hand lever 334 which allows the one-revolution clutch 332 to rotate the cam 178 a single revolution, to operate the sole beveling knives 184, the sole shouldering knives 186 and the heel shouldering knives 187. When the various cutting operations have been completed the machine is automatically declutched and comes to rest. It is generally 85 customary to make the beveling cuts and to form the shoulders on the heel before the sole shoulder cuts but the order of operation of the knives may be changed if desired. 90

95 When the pressure on the treadle 172 is released the sliding beds 192 are automatically moved away from one another and the holdown clamp 212 is automatically raised from the sole of the shoe. Finally the work support 112 which is now unlocked is moved 100 away from the machine to remove the shoe and the treadle rod 480 is depressed to remove the heel from the heel clamp.

105 While the holdown clamp 212 has been described and illustrated as part of the machine, it has been found that such a clamp is not an essential element in the operation of the machine since the crease plates may be constructed to resist the upward pressure of the post 120 and to hold the shoe in position 110 to have its heel-seat fitted for the reception of the heel.

Having thus described my invention, what I claim as new and desire to secure by Letters Patent of the United States is:

115 1. An improvement in methods of making shoes which consists in positioning a heel, positioning a sole in correlated arrangement with the heel and determined by the heel, and trimming the heel to form shoulders thereon and the sole to form a reduced heel-seat portion thereof and heel-breast-receiving shoulders thereon while the heel and the sole are in their correlated positions, which heel-breast-receiving shoulders are substantially 120 complementary to the shoulders formed upon the heel to insure the proper positioning of the heel upon the sole of the shoe. 125

130 2. An improvement in methods of making shoes which consists in positioning a

heel to be operated upon, positioning a sole to be operated upon in correlated arrangement with the heel and determined by the heel and simultaneously trimming the heel to form shoulders thereon and the sole to form a reduced heel-seat portion thereof and heel-breast-receiving shoulders thereon while the heel and the sole are in their correlated positions, which heel-breast-receiving shoulders are substantially complementary to the shoulders formed upon the heel to insure the proper positioning of the heel upon the sole of the shoe.

3. An improvement in methods of making shoes which consists in positioning a heel to be operated upon, positioning a sole to be operated upon in correlated arrangement with the heel and determined by the heel, and trimming the heel to form sole-engaging shoulders thereon and the sole to form heel-breast-receiving shoulders thereon while the heel and the sole are in their correlated positions, which heel-breast-receiving shoulders are substantially complementary to the shoulders formed upon the heel to insure the proper positioning of the heel upon the sole of the shoe.

4. An improvement in methods of making shoes which consists in positioning a Louis heel to be operated upon, positioning a sole to be operated upon in correlated arrangement with the heel and determined by the heel, and simultaneously trimming the heel to form shoulders thereon and the sole to form a reduced heel-seat portion and heel-breast-receiving shoulders thereon while the heel and sole are in their correlated positions, which heel-breast-receiving shoulders are fitted and arranged to register with the shoulders formed upon the heel of the shoe.

5. An improvement in methods of making shoes which consists in positioning a Louis heel to be operated upon, positioning a sole attached to a shoe upper to be operated upon in correlated arrangement with the heel and determined by the heel, and simultaneously trimming the heel to form shoulders thereon and the sole to form a reduced heel-seat portion and heel-breast-receiving shoulders thereon while the heel and the sole are in their correlated positions, which heel-breast-receiving shoulders are complementary to the shoulders formed upon the heel and are fitted and arranged to position the heel upon the sole of the shoe.

6. A machine for trimming heels having, in combination, means for positioning a heel to be trimmed, and a pair of knives mounted for movement transversely and forwardly of the heel and constructed and arranged to form shoulders upon the heel.

7. A machine for trimming heels having, in combination, means for positioning a heel to be trimmed, and a knife mounted for movement transversely and forwardly of the heel

and constructed and arranged to form a shoulder upon the heel.

8. A machine for trimming heels having, in combination, means for positioning a heel to be trimmed, means for locking the heel in the heel positioning means, and a pair of knives mounted for movement transversely and forwardly of the heel and constructed and arranged to form shoulders upon the heel.

9. A machine for trimming heels having, in combination, means for positioning a heel to be trimmed, means for locking the heel in the heel positioning means, and a knife mounted for movement transversely and forwardly of the heel and constructed and arranged to form a shoulder upon the heel.

10. A machine for trimming a Louis heel provided with a projecting lip having a feather edge, having in combination, means for positioning the heel to be trimmed, means for locking the heel in the heel positioning means, and a pair of knives constructed and arranged to form shoulders of substantial surface area at the ends of the feather edge and at a substantial angle to the feather edge.

11. A machine for trimming a Louis heel provided with a projecting lip having a feather edge, an attaching surface having a marginal rim, and a pair of breast edges, having, in combination, a plate for supporting the heel to be trimmed, members for positioning the heel upon the plate, means for locking the heel so positioned, and knives for truncating portions of the heel formed between the feather edge of the lip, the rim of the attaching face of the heel, and the heel breast edges, to form shoulders upon the heel.

12. A machine for trimming a Louis heel provided with a projecting lip having a feather edge, having, in combination, means for locking a heel in the machine, and means for forming at the ends of the feather edge shoulders which extend rearwardly of the heel and toward the sides of the heel.

13. A machine for trimming a Louis heel provided with a projecting lip having a feather edge, having, in combination, means for locking a heel in the machine, and means for forming at the ends of the feather edge a pair of shoulders extending rearwardly of the heel as they approach the sides of the heel and forwardly of the shoe as they approach the attaching face of the heel.

14. A machine for trimming a Louis heel provided with a projecting lip terminating in a feather edge, having, in combination, means for positioning a heel in the machine, means for locking the heel in the machine, and means for forming at the ends of the feather edge a pair of shoulders extending rearwardly of the heel and toward the sides of the heel.

15. A machine for trimming a Louis heel provided with a projecting lip terminating in a feather edge, having, in combination, means

for positioning the heel in the machine, means for locking a heel in the machine, and means for forming at the ends of the feather edge a pair of shoulders extending rearwardly of the heel as they approach the sides of the heel and forwardly of the shoe as they approach the attaching face of the heel.

16. A machine for trimming a Louis heel provided with a lip terminating in a feather edge and a pair of breast edges, having, in combination, means for locking a heel in the machine, and means for forming upon the heel a pair of shoulders extending from the feather edge of the lip to the sides of the heel and formed by a pair of substantially plane surfaces each defined by two lines intersecting at a point on the breast edge of the heel, one of said lines extending forwardly of the shoe toward the center of the feather edge from said point and the other line extending forwardly of the heel and toward the attaching face of the heel from said point.

17. A heel trimming machine having, in combination, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, and cutters for trimming the heel.

18. A heel trimming machine having, in combination, a surface for supporting a heel to be trimmed, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, and cutters for trimming the heel.

19. A heel trimming machine having, in combination, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, and means for trimming the heel.

20. A heel trimming machine having, in combination, a surface for supporting a heel to be trimmed, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage

the heel prior to the engagement of said abutments with the heel, and means for trimming the heel.

21. A heel trimming machine having, in combination, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, spring actuated means for normally urging the abutments and the clamps against said heel, and cutters for trimming the heel.

22. A heel trimming machine having, in combination, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, means for normally urging the abutments and the clamps against the heel, means for locking the heel against movement in the machine, and cutters for trimming the heel.

23. A heel trimming machine having, in combination, abutments for engaging a heel to be trimmed to position the heel in the machine lengthwise of the heel, clamps for engaging the sides of the heel to position the heel in the machine laterally of the heel, said clamps being mounted for movement with one of the abutments and arranged to engage the heel prior to the engagement of said abutments with the heel, means for normally urging the abutments and the clamps against the heel, means for locking the heel against movement in the machine, and knives for trimming the heel.

24. A heel trimming machine having, in combination, an abutment constructed and arranged for contact with the rear portion of a Louis heel, another abutment constructed and arranged for contact with the breast of the heel, clamps arranged for contact with the sides of the heel and mounted for movement with one of the said abutments, compensating means for causing the clamps and the abutments to accommodate different sizes and shapes of heels, means comprising a pawl and ratchet for locking the clamps and the abutments against the heel, and knives for trimming the heel.

25. A heel trimming machine having, in combination, a surface for supporting a Louis heel provided with an attaching face and a projecting lip, means for positioning and locking the heel in the machine with the attaching face of the heel resting upon said supporting surface and the lip extending for

- wardly of the machine, a knife moving forwardly and laterally of the heel and having its cutting edge inclined at an angle to the supporting surface to form shoulders at the 5 marginal portions of the lip, and means for preventing rearward springing of the knife, which means comprises a shoulder formed on the supporting surface against which shoulder the cutting edge of the knife contacts 10 during the heel trimming operation.
26. A heel trimming machine having, in combination, a surface for supporting a Louis heel provided with an attaching face and a projecting lip, means for positioning and locking the heel in the machine with the attaching face of the heel resting upon said supporting surface and the lip extending forwardly of the machine, a knife moving forwardly and laterally of the heel and having 15 its cutting edge inclined at an angle to the supporting surface to form shoulders at the marginal portions of the lip, and means for preventing rearward springing of the knife.
27. A heel trimming machine having, in combination, a surface for supporting a Louis heel having an attaching face and a projecting lip, means for positioning and locking the heel in the machine with the attaching face of the heel resting upon said supporting surface and the lip extending forwardly of the machine, and a knife moving forwardly and laterally of the heel and having 20 its cutting edge inclined at an angle to the supporting surface to form shoulders at the marginal portions of the lip, and means for preventing rearward springing of the knife.
28. A heel trimming machine having, in combination, a surface for supporting a Louis heel having an attaching face and a projecting lip, means for positioning and locking 25 the heel against movement in the machine with the attaching face of the heel resting upon said supporting surface and the lip extending forwardly of the machine, and a knife moving forwardly and laterally of the heel and having its cutting edge lying in a plane extending upwardly and rearwardly 30 from the heel supporting surface to form shoulders at the marginal portions of the lip.
29. A heel trimming machine having, in combination, a surface for supporting a Louis heel having an attaching face and a projecting lip, means for positioning and locking the heel against movement in the machine, with the attaching face of the heel resting upon said supporting surface and the lip extending forwardly of the machine, a knife moving forwardly and laterally of the heel and having its cutting edge inclined at 35 an angle to the supporting surface to form shoulders at the marginal portions of the lip, and means for initially setting the knife relatively to the heel positioned in the machine.
30. A heel trimming machine having, in combination, an abutment arranged for contact with the rear portion of a heel, another 40 abutment arranged for contact with the breast of the heel, clamps arranged for contact with the sides of the heel and mounted for movement with the first-named abutment, compensating means to cause the 45 clamps and the first-named abutment to accommodate different sizes and shapes of heels, spring actuated means for normally urging the abutments and clamps against the heel, and means for trimming the heel.
31. A heel-seat fitting and heel trimming machine having, in combination, means for trimming a heel, and means for operating upon the sole of a shoe to trim the heel-seat portion thereof to a size determined by the 50 heel.
32. A heel-seat fitting and heel trimming machine having, in combination, means for receiving a heel, means for receiving the sole of a shoe, means controlled by the heel for determining the position of the sole in the sole receiving means, means for trimming the heel in the heel receiving means, and means for trimming the sole of the shoe in the sole receiving means to shape the heel-seat portion 55 thereof for the reception of the trimmed heel.
33. A heel-seat fitting and heel trimming machine having, in combination, means for receiving a Louis heel, means for receiving the sole of a shoe, means controlled by the heel for positioning the sole in the sole receiving means in correlated arrangement with the heel, means for trimming the heel in the heel receiving means, and means for trimming the sole in the sole receiving means, 60 said heel and sole trimming means being constructed and arranged to provide substantially complementary shoulders on the heel and on the sole.
34. A heel-seat fitting and heel trimming machine having, in combination, means for receiving a heel, means for receiving the sole of a shoe, means positively controlled by the heel for determining the position of the sole in the sole receiving means, means for trimming the sole in the sole receiving means, and means for trimming the heel in the heel receiving means, said heel trimming means and said sole trimming means being constructed and arranged to form complementary 65 shoulders on the heel and on the sole respectively.
35. A heel-seat fitting and heel trimming machine having, in combination, means for receiving a Louis heel, means for receiving the sole of a shoe, means for positioning the heel in the heel receiving means, means for positioning the sole in the sole receiving means, means controlled by the heel in the heel receiving means for determining the position of the sole in the sole receiving means, means for trimming the heel in the heel receiving means, and means for trimming the sole in the sole receiving means, said trimming means being constructed and arranged 70

to form complemental shoulders upon the heel and upon the sole.

36. A heel-seat fitting and heel trimming machine having, in combination, means for receiving a Louis heel, means for receiving the sole of a shoe, sole trimming means for forming a reduced heel-seat portion and a pair of heel-breast-receiving shoulders upon the sole positioned in the sole receiving means, means for trimming a heel in the heel receiving means to form shoulders thereon, and means controlled by the heel for determining the position of the sole in the sole receiving means, said heel positioning means and said sole positioning means being so constructed and arranged that the heel-breast-receiving shoulders formed on the sole will register with the shoulders formed on the heel after the trimming operations have been completed.

37. A heel-seat fitting and heel trimming machine, having, in combination, means for receiving a Louis heel, means for receiving the sole of a shoe, means controlled by the heel for positioning the sole in the sole receiving means, in correlated arrangement with the heel, sole trimming means for forming a reduced heel-seat portion and a pair of heel-breast-receiving shoulders upon the sole in the sole receiving means, and trimming means for truncating a portion of the heel to form thereon shoulders complemental to the heel-breast-receiving shoulders formed on the sole.

38. A heel-seat fitting and heel trimming machine having, in combination, members for positioning a Louis heel to be trimmed, knives mounted for movement transversely and forwardly of the heel and constructed and arranged to form shoulders upon the heel, means for receiving the sole of a shoe, means controlled by the heel for positioning the sole in the sole receiving means in correlated arrangement with the heel, knives for trimming the sole to form heel-breast-receiving shoulders thereon, said knives being constructed and arranged to cause the shoulders formed upon the heel and the heel-breast-receiving shoulders to be complemental to each other, and means for operating the knives.

39. A heel-seat fitting and heel trimming machine having, in combination, means comprising a heel support and members for positioning a Louis heel to be trimmed, knives mounted for movement transversely and forwardly of the heel and constructed and arranged to form shoulders upon the heel, means for receiving a sole attached to a shoe, means controlled by the heel for positioning the sole in the sole receiving means in correlated arrangement with the heel, knives constructed and arranged to trim the sole to form heel-breast-receiving shoulders which are complemental to the shoulders formed

upon the heel, and means for operating the knives.

40. A heel-seat fitting and heel trimming machine having, in combination, means comprising a heel support and members for positioning a Louis heel to be trimmed, knives mounted for movement transversely and forwardly of the heel and constructed and arranged to form shoulders upon the heel, means for locking the heel in the heel positioning means, means for receiving the sole of a shoe, means controlled by the heel for positioning the sole in the sole receiving means in correlated arrangement with the heel, means for trimming the sole of the shoe to form upon the sole heel-breast-receiving shoulders which are complemental to the shoulders formed upon the heel, and means for operating the knives.

41. A heel-seat fitting and heel trimming machine for use in the manufacture of shoes having Louis heels, having, in combination, means comprising a heel support and members for positioning a heel upon the support, a pair of knives constructed and arranged to form at the ends of the feather edge of the breast of the heel and at a substantial angle to the feather edge shoulders of substantial surface areas, means for locking the heel in the heel positioning means to provide against movement of the heel in the machine during the shoulder forming operation, means for receiving the sole of a shoe, means controlled by the heel for positioning the sole in the sole receiving means in correlated arrangement with the heel, means for trimming the sole of the shoe to form upon the sole heel-breast-receiving shoulders constructed and arranged to mate with the shoulders formed on the heel, and means for operating the knives.

42. A heel-seat fitting and heel trimming machine for use in the manufacture of shoes having Louis heels, having, in combination, means comprising a heel support and members for positioning a heel and for locking it in the heel positioning means to provide against movement of the heel in the machine, knives constructed and arranged to truncate portions of the heel included between the feather edge of the lip of the breast of the heel, the rim of the attaching face of the heel and the heel-breast edges of the heel to form shoulders, means for receiving the sole of a shoe, means controlled by the heel for positioning the sole in the sole receiving means in correlated arrangement with the heel, knives for trimming the sole of the shoe to form on the sole of the shoe heel-breast-receiving shoulders which mate with the shoulders formed upon the heel, and means for operating the knives.

43. A heel-seat fitting and heel trimming machine for use in the manufacture of shoes, having, in combination, means including a

- heel support and members for positioning a heel and for locking the heel in the heel positioning means to provide against movement of the heel in the machine, knives for truncating portions of the heel included between the feather edge of the lip of the breast of the heel, the rim of the attaching face of the heel and the breast edges of the heel to form shoulders, means for receiving the sole of a shoe, means controlled by the heel for positioning the sole in the sole receiving means in correlated arrangement with the heel, knives for trimming a sole attached to a shoe to form on the sole of the shoe heel-breast-receiving shoulders which mate with the shoulders formed upon the heel, and means for operating the knives.
44. A heel-seat fitting and heel trimming machine having, in combination, means for securing a Louis heel in position, means for forming at the ends of the feather edge of the breast of the heel a pair of shoulders which extend rearwardly of the heel and toward the sides of the heel, means for receiving the sole of a shoe, means controlled by the heel for positioning the sole in the sole receiving means in correlated arrangement with the heel, knives for trimming the sole of a shoe to form upon the sole heel-breast-receiving shoulders which mate with the shoulders formed upon the heel when the heel is correctly positioned upon the shoe.
45. A heel-seat fitting and heel trimming machine having, in combination, means including a heel support and heel engaging members for securing a Louis heel in position, knives for forming at the ends of the feather edge of the breast of the heel a pair of shoulders which extend rearwardly of the heel as they approach the sides of the heel and which extend forwardly of the heel as they approach the attaching face of the heel, means for receiving the sole of a shoe, means controlled by the heel for positioning the sole in the sole receiving means in correlated arrangement with the heel, knives for trimming the sole of the shoe to form on the sole of the shoe heel-breast-receiving shoulders which are complementary to shoulders formed upon the heel, and means for operating the knives.
46. A heel-seat fitting and heel trimming machine having, in combination, means including a heel support and heel engaging members for positioning a Louis heel and for securing the heel in position, knives mounted for rectilinear movement for forming at the ends of the feather edge of the breast of the heel a pair of shoulders which extend rearwardly of the heel as they approach the sides of the heel and which extend forwardly of the heel as they approach the attaching face of the heel, means for receiving the sole of a shoe, means controlled by the heel for positioning the sole in the sole receiving means in correlated arrangement with the heel, knives for forming on the sole of the shoe heel-breast-receiving shoulders which mate with the shoulders formed upon the heel, and means for operating the knives.
47. A heel-seat fitting and heel trimming machine having, in combination, means including a heel support and members for positioning a Louis heel, means including a pawl and ratchet for securing the heel against movement, knives for forming at the ends of the feather edge at the breast of the heel a pair of shoulders each of which extends rearwardly of the heel and toward a side of the heel, means for receiving the sole of a shoe, means controlled by the heel for positioning the sole in the sole receiving means in correlated arrangement with the heel, knives constructed and arranged to trim the sole of the shoe for forming on the sole heel-breast-receiving shoulders which mate with the shoulders on the heel when the heel is accurately positioned on the shoe, and means for operating the knives.
48. A heel-seat fitting and heel trimming machine having, in combination, means including a heel support and members for positioning a Louis heel in the machine, means for positioning a heel and for securing it against movement in the machine, knives for forming at the ends of the feather edge of the breast of the heel a pair of shoulders which extend rearwardly of the heel as they approach the sides of the heel and which extend forwardly of the shoe as they approach the attaching face of the heel, means for receiving the sole of a shoe, means controlled by the heel for positioning the sole in the sole receiving means in correlated arrangement with the heel, knives constructed and arranged to trim the sole of the shoe for forming on the sole shoulders which mate with the shoulders formed upon the heel, and means for operating the knives.
49. A heel-seat fitting and heel trimming machine having, in combination, means including a heel support and members for positioning a Louis heel, means for securing the heel in position, knives for forming at the ends of the feather edge of the breast of the heel a pair of shoulders which extend rearwardly of the heel as they approach the sides of the heel and which extend forwardly of the shoe as they approach the attaching face of the heel, means for receiving the sole of a shoe, means controlled by the heel for positioning the sole in the sole receiving means in correlated arrangement with the heel, knives constructed and arranged to trim a sole attached to a shoe for forming on the sole shoulders which mate with the shoulders

formed upon the heel when the heel is positioned upon the shoe, and means for operating the knives.

50. A heel-seat fitting and heel trimming machine having, in combination, means including a heel support and members for positioning a Louis heel upon the support, means for securing the heel against movement in the heel positioning means, knives for trimming the heel to form shoulders thereon, crease plates, means controlled by the heel and cooperating with the crease plates for positioning a sole attached to a shoe upper, knives for trimming the sole to form a reduced heel-seat portion and to form a pair of heel-breast-receiving shoulders arranged to register with the shoulders formed on the heel and each defined by two lines intersecting at a point on the tread surface of the sole rearwardly of the breast line of the sole and at the lateral edge of the sole, one of the lines extending forwardly of the sole and toward the center of the said breast line and the other line extending forwardly of the sole and toward the attaching face of the sole, and means for operating the knives.

51. A heel-seat fitting and heel trimming machine having, in combination, means including a heel support and members for positioning a Louis heel, means for locking the heel against movement in the heel positioning means, knives for trimming the heel to form shoulders thereon, crease plates, a back gage controlled by the heel and shaped and arranged to cooperate with the crease plates for positioning a sole attached to a shoe, knives for trimming the sole to form thereon a reduced heel-seat portion and a pair of heel-breast-receiving shoulders undercut heightwise of the sole and extending from the lateral margins of the reduced heel-seat portion substantially at the heel breast line of the sole rearwardly and laterally of the sole, said heel-breast-receiving shoulders being constructed to register with the shoulders formed on the heel, and means for operating the knives.

52. A heel-seat fitting and heel trimming machine having, in combination, means including a heel support and members for positioning a Louis heel provided with a lip having a feather edge to be trimmed, a pair of knives constructed and arranged to form shoulders of substantial surface area at the lateral portions of the feather edge and at a substantial angle to the feather edge, means for locking the heel against movement in the heel positioning means, crease plates, a back gage controlled by the heel and shaped and arranged to cooperate with the crease plates for positioning a sole attached to a shoe, a pair of knives for trimming the sole of the shoe for forming thereon a reduced heel-seat portion and a pair of heel-breast-receiving shoulders extending from the lateral mar-

gins of the reduced heel-seat portion substantially at the heel breast line of the sole rearwardly and laterally of the sole, said heel-breast-receiving shoulders and the shoulders of the heel being arranged to register with one another to facilitate the positioning of the heel upon the sole of the shoe, and means for operating the knives.

53. A heel-seat fitting and heel trimming machine having, in combination, knives for forming shoulders upon a Louis heel, means including a gage controlled by the heel for positioning a sole of a shoe, knives for trimming the sole to form thereon a reduced heel-seat portion and a pair of heel-breast-receiving shoulders undercut heightwise of the sole and extending from the lateral margins of the reduced heel-seat portion substantially at the heel breast line of the sole rearwardly and laterally of the sole, the shoulders formed upon the heel being substantially complements of the heel-breast-receiving shoulders and being constructed and arranged to register with the heel-breast-receiving shoulders, and means for operating the knives.

54. A heel-seat fitting and heel trimming machine having, in combination, knives for forming shoulders upon a Louis heel, means including a gage controlled by the heel for positioning a sole, knives for trimming the sole to form thereon a reduced heel-seat portion and a pair of heel-breast-receiving shoulders each of which is defined by two lines intersecting at a point on the tread surface of the sole rearwardly of the breast line of the sole and at the lateral edge of the sole, one of the lines extending forwardly of the sole and toward the center of the said breast line and the other line extending forwardly of the sole and toward the attaching face of the sole, the shoulders formed upon the heel being substantial complements of the heel-breast-receiving shoulders formed on the sole and being constructed and arranged to register with the heel-breast receiving shoulders, and means for operating the knives.

55. A heel-seat fitting and heel trimming machine having, in combination, means for positioning a Louis heel, knives for forming upon the heel a pair of shoulders extending from the feather edge of the breast of the heel to the sides of the heel, each of the shoulders being defined by two lines intersecting at a point upon each of the breast edges, one of the said lines extending forwardly of the shoe toward the center of the feather edge from said point and the other line extending forwardly of the heel and toward the attaching surface of the heel from said point, means for receiving the sole of a shoe, means controlled by the heel for positioning the sole in the sole receiving means in correlated arrangement with the heel, knives for trimming the sole to form heel-breast-receiving shoulders which facilitate the correct posi-

tioning of the heel upon the sole, and means for operating the knives.

56. A heel-seat fitting and heel trimming machine having, in combination, mechanism including a heel support and heel engaging members the positions of which control said mechanism for determining the lengthwise position of a sole to be trimmed in the machine, knives for trimming the sole to form thereon a reduced heel-seat portion and a pair of heel-breast-receiving shoulders extending from the lateral margins of the reduced heel-seat portion substantially at the heel breast line of the sole rearwardly and laterally of the sole, said means for locating the heel and the sole in correlated positions in the machine being constructed and arranged to insure that the shoulders formed upon the heel and the heel-breast-receiving shoulders formed on the sole are substantially complementary to one another and are arranged to register with one another to facilitate the correct positioning of the heel upon the sole of the shoe, and means for operating the knives.
- 10 5 15 20 25 30 35 40 45 50 55 60 65

57. A heel-seat fitting and heel trimming machine for use in the manufacture of shoes having Louis heels having, in combination, means including a heel support and heel engaging members for positioning a heel to be trimmed and for locking the heel in the heel positioning means, knives for truncating a portion of the heel included between the feather edge of the lip of the heel, the rim of the attaching face of the heel and the heel breast edges to form shoulders thereon, crease plates, means controlled by the heel and constructed and arranged to cooperate with the crease plates for positioning a sole attached to a shoe, knives for trimming the sole to form thereon a reduced heel-seat portion and a pair of heel-breast-receiving shoulders each defined by two lines intersecting at a point on the tread surface of the sole rearwardly of the breast line of the sole and at a lateral edge of the sole, one of the lines extending forwardly of the sole and toward the center of the said breast line and the other line extending forwardly of the sole and toward the attaching face of the sole, said shoulders formed upon the heel and the heel-breast-receiving shoulders being substantial complements of each other and being arranged to register with each other to facilitate the correct positioning of the heel upon the sole, and means for operating the knives.
- 10 15 20 25 30 35 40 45 50 55 60 65

58. A heel-seat fitting and heel trimming machine having, in combination, means for positioning in the machine a Louis heel to be trimmed, knives mounted for movement transversely and forwardly of the heel and constructed and arranged to form shoulders upon the heel, crease plates, means controlled by the heel and arranged to cooperate with the crease plates for positioning a sole to be trimmed in correlated arrangement with the heel, knives for trimming the sole to form

thereon a reduced heel-seat portion and a pair of heel-breast-receiving shoulders extending from the lateral margins of the reduced heel-seat portion substantially at the heel breast line of the sole rearwardly and laterally of the sole, said means for locating the heel and the sole in correlated positions in the machine being constructed and arranged to insure that the shoulders formed upon the heel and the heel-breast-receiving shoulders formed on the sole are substantially complementary to one another and are arranged to register with one another to facilitate the correct positioning of the heel upon the sole of the shoe, and means for operating the knives.

59. A heel-seat fitting and heel trimming machine comprising means for positioning and locking in the machine a Louis heel to be trimmed, knives mounted for movement transversely and forwardly of the heel for forming shoulders upon the heel, crease plates, means controlled by the heel constructed and arranged to cooperate with the crease plates for positioning a sole attached to a shoe, knives for trimming the sole to form heel-breast-receiving shoulders thereon, said knives being mounted for movement in a path substantially parallel to the path of movement of the aforesaid knives, said shoulders formed upon the heel and the heel-breast-receiving shoulders formed on the sole being substantially complementary to each other and being arranged to register with each other to facilitate the correct positioning of the heel upon the sole of the shoe, and means for operating the knives.

60. A heel-seat fitting and heel trimming machine comprising means for positioning and locking a Louis heel with its attaching face down and its protruding lip extending forwardly of the machine, knives having their cutting edges extending downwardly and forwardly of the machine and mounted for movement transversely and forwardly of the heel to form shoulders upon the projecting lip of the heel, means controlled by the heel for positioning the sole of a shoe in correlated arrangement with the heel, knives having their cutting edges extending downwardly and forwardly of the machine for forming heel-breast-receiving shoulders upon the sole of the shoe, the knives for operating on the sole being mounted for movement in paths substantially parallel to the respective paths of movement of the knives for operating on the heel, said means for locating the heel and the sole in correlated positions in the machine being constructed and arranged to insure that the shoulders formed upon the heel and the heel-breast-receiving shoulders formed on the sole are substantially complementary to each other and being arranged to facilitate the correct positioning of the heel

upon the shoe, and means for operating the knives.

61. A heel-seat fitting and heel trimming machine having, in combination, a shoe support, crease plates constructed and arranged to enter the rand crease of a shoe on the support, means for positioning a Louis heel in the machine, means controlled by the heel constructed and arranged to cooperate with the support and the crease plates for positioning the shoe in the machine in correlated arrangement with the heel, knives mounted for reciprocation in the general direction of the length of the sole of the shoe for trimming the marginal portions of the heel-seat portion of the sole, knives mounted for rectilinear movement transversely of the length of the shoe to form heel-breast-receiving shoulders substantially at the heel breast line of the sole, knives for forming upon the heel shoulders which are substantially complementary to the heel-breast-receiving shoulders, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the shoe, and means for operating the knives.
62. A heel-seat fitting and heel trimming machine constructed and arranged to operate upon the heel portion of a sole which is attached to a shoe upper and is in an undistorted condition having, in combination, a shoe support, crease plates constructed and arranged to enter the rand crease of a shoe carried by the support without distorting the sole, means for positioning a Louis heel in the machine, means controlled by the heel constructed and arranged to cooperate with the support and the crease plates for positioning the shoe in the machine in correlated arrangement with the heel, knives mounted for reciprocation in the general direction of the length of the shoe for trimming the marginal portions of the heel-seat portion of the sole of the shoe, knives mounted for reciprocation transversely of the length of the shoe substantially at the breast line of the sole completely to sever the material trimmed from the marginal portions of the heel-seat portion of the sole and constructed and arranged to form heel-breast-receiving shoulders, knives for forming upon the heel shoulders which are substantial complements of the heel-breast-receiving shoulders and which are arranged to insure the correct positioning of the heel upon the sole of the shoe, and means for operating the knives.
63. A heel-seat fitting and heel trimming machine for operating upon the heel portion of a sole which is attached to a shoe and is in an undistorted condition having, in combination, a shoe support, crease plates constructed and arranged to enter the rand crease of a shoe carried by the support without distorting the sole, means for positioning a Louis heel in the machine, means controlled by the heel

constructed and arranged to cooperate with the support and the crease plates for positioning the shoe in the machine in correlated arrangement with the heel, knives mounted for reciprocation in the general direction of the length of the shoe for trimming the marginal portions of the heel-seat portion of the sole at a steep inclination to the heel attaching face of the sole, knives mounted for reciprocation transversely of the length of the shoe to form heel-breast-receiving shoulders substantially at the heel breast line of the sole, knives for forming upon the heel shoulders which are substantially complementary to the heel-breast-receiving shoulders, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the shoe, and means for operating the knives.

64. A heel-seat fitting and heel trimming machine having, in combination, a support for a shoe, knives mounted for reciprocation in the general direction of the length of the shoe for trimming the marginal portions of the heel-seat portion of the sole of the shoe at a steep inclination to the attaching face of the sole to form a wide heel-seat having its full thickness throughout substantially its entire width, means for positioning a Louis heel in the machine, means controlled by the heel for positioning the shoe in the machine in correlated arrangement with the heel, knives mounted for reciprocation transversely of the length of the shoe substantially at the heel breast line of the sole to form heel-breast-receiving shoulders, knives for forming upon the heel shoulders which are substantially complementary to the heel-breast-receiving shoulders, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.

65. A heel-seat fitting and heel trimming machine having, in combination, a shoe support, crease plates constructed and arranged to enter the rand crease of a shoe on the support, means for positioning a Louis heel in the machine, means controlled by the heel constructed and arranged to cooperate with the support and the crease plates for positioning the shoe in the machine in correlated arrangement with the heel, knives mounted for reciprocation in the general direction of the length of the shoe for trimming the marginal

- portions of the heel-seat portion of the sole of the shoe, knives having rectilinear movement and mounted for reciprocation transversely of the length of the shoe substantially 50 ranged to register with one another to facilitate the correct positioning of the heel upon the sole of the shoe, and means for operating the knives.
- 5 at the heel breast line of the sole for forming heel-breast-receiving shoulders on the sole, knives for forming upon the heel shoulders which are substantially complementary to the heel-breast-receiving shoulders, said means 55 70 machine having, in combination, a shoe support, crease plates constructed and arranged to enter the rand crease of a shoe on the support without distorting the sole, means for positioning a Louis heel in the machine, means controlled by the heel constructed and arranged to cooperate with the support and these crease plates for positioning the shoe in the machine in correlated arrangement with the heel, means for trimming the marginal portions of the heel-seat portion of the sole of the shoe, a pair of knives mounted for movement transversely of the length of the sole for forming heel-breast-receiving shoulders, said knives having cutting edges set at an angle to and disposed transversely of the attaching face of the sole, a pair of knives for forming upon the heel shoulders which are substantially complementary to the heel-breast-receiving shoulders, said means for 60 75 80 85 90 95 100 105 110 115 120 125 130
- 10 for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.
- 15 66. A heel-seat fitting and heel trimming machine having, in combination, a shoe support, crease plates constructed and arranged to enter the rand crease of a shoe on the support, means for positioning a Louis heel in the machine, means controlled by the heel 65 90 95 100 105 110 115 120 125 130
- 20 constructed and arranged to cooperate with the support and the crease plates for positioning the shoe in the machine in correlated arrangement with the heel, means for trimming the marginal portions of the heel-seat portion of the sole of the shoe while the sole is in an undistorted condition, knives mounted for reciprocation transversely of the length of the sole to form heel-breast-receiving shoulders substantially at the breast line of 25 90 95 100 105 110 115 120 125 130

- 40 the sole, and means for operating the knives.
67. A heel-seat fitting and heel trimming machine having, in combination, a shoe support, crease plates constructed and arranged to enter the rand crease of a shoe on the support, means for positioning a Louis heel in the machine, means controlled by the heel constructed and arranged to cooperate with the support and the crease plates for positioning the shoe in the machine in correlated arrangement with the heel, beveling knives having cutting edges inclined to the attaching face of the sole of the shoe and constructed and arranged to trim the marginal portions of the sole of the shoe to fit the heel-seat portion of the sole for the reception 45 110 115 120 125 130
- 50 of the heel, shoulderng knives having cutting edges substantially parallel with the cutting edges of the beveling knives and mounted for movement transversely of the sole for forming heel-breast-receiving shoulders on the sole, knives for forming upon the heel shoulders substantially complementary to the heel-breast-receiving shoulders, said means for 55 115 120 125 130
- 55 locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.
- 60 68. A heel-seat fitting and heel trimming machine having, in combination, a shoe support, crease plates constructed and arranged to enter the rand crease of a shoe on the support without distorting the sole, means for positioning a Louis heel in the machine, means controlled by the heel constructed and arranged to cooperate with the support and these crease plates for positioning the shoe in the machine in correlated arrangement with the heel, means for trimming the marginal portions of the heel-seat portion of the sole of the shoe, a pair of knives mounted for movement transversely of the length of the sole for forming heel-breast-receiving shoulders, said knives having cutting edges set at an angle to and disposed transversely of the attaching face of the sole, a pair of knives for forming upon the heel shoulders which are substantially complementary to the heel-breast-receiving shoulders, said means for 65 120 125 130
- 65 locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.

tioning of the heel upon the sole of the shoe, and means for operating the knives.

70. A heel-seat fitting and heel trimming machine having, in combination, a shoe support, crease plates formed and arranged to enter the rand crease of a shoe on the support, a machine frame, a pair of sliding beds mounted for movement widthwise of the shoe upon the machine frame, means for moving the sliding beds toward and away from one another, means for positioning a Louis heel in the machine, means controlled by the heel constructed and arranged to cooperate with the support and the crease plates for positioning the shoe in the machine in correlated arrangement with the heel, a knife carried by each of the sliding beds and arranged to move lengthwise of the sole of the shoe for trimming the marginal portions of the sole to fit the heel-seat portion of the sole of the shoe for the reception of the heel, another knife carried by each of the sliding beds and constructed and arranged to move transversely of the shoe substantially at the heel breast line of the sole to form heel-breast-receiving shoulders, means for reciprocating the knives relatively to the sliding beds and the support, means for forming upon the heel shoulders which are substantially complementary to the heel-breast-receiving shoulders, said means for locating the heel and the sole in correlated positions in the machine being constructed and arranged to insure that the shoulders formed upon the heel and the heel-breast-receiving shoulders formed on the sole are complementary to one another and are arranged to register with one another to facilitate the correct positioning of the heel upon the sole of the shoe, and means for operating the knives.

71. A heel-seat fitting and heel trimming machine having, in combination, a shoe support, a machine frame, a pair of sliding beds mounted for movement toward and away from one another in the machine frame, crease plates constructed and arranged to enter the rand crease of a shoe on the support, which plates are carried by the sliding beds, means for moving the sliding beds toward and away from one another, means for positioning a Louis heel in the machine, means controlled by the heel constructed and arranged to cooperate with the support and the crease plates for positioning the shoe in the machine in correlated arrangement with the heel, a reciprocating knife carried by each of the sliding beds and arranged for movement lengthwise of the sole of the shoe for trimming the marginal portions of the heel-seat portion of the sole, another knife carried by each of the sliding beds and arranged for movement transversely of the length of the shoe to form heel-breast-receiving shoulders substantially at the heel breast line of the sole, means for reciprocating the

knives relatively to the sliding beds and the support, means for forming upon the heel shoulders which are substantially complementary to the heel-breast-receiving shoulders, said means for locating the heel and the sole in correlated positions in the machine being constructed and arranged to insure that the shoulders formed upon the heel and the heel-breast-receiving shoulders formed on the sole are complementary to one another and are arranged to register with one another to facilitate the correct positioning of the heel upon the sole of the shoe, and means for operating the knives.

72. A heel-seat fitting and heel trimming machine having, in combination, a support for a shoe, a machine frame, a pair of sliding beds mounted for movement toward and away from one another in the machine frame, means for positioning a Louis heel in the machine, means controlled by the heel constructed and arranged to cooperate with the support for positioning the shoe in the machine in correlated arrangement with the heel, a knife carried by each of the sliding beds which knives are mounted for reciprocation lengthwise of the sole of a shoe on the support, another knife carried by each sliding bed and arranged to move transversely of the length of the shoe for forming heel-breast-receiving shoulders substantially at the heel breast line of the sole of the shoe, means for operating the lengthwise moving knives relatively to the shoe support and the sliding beds, means for operating the transversely moving knives relatively to the shoe support and sliding beds, means for initially setting the transversely moving knives in position relatively to the sliding beds, means for forming upon the heel shoulders which are substantially complementary of the heel-breast-receiving shoulders, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.

73. A heel-seat fitting and heel trimming machine having, in combination, a shoe support, crease plates constructed and arranged to enter the rand crease of a shoe on the support and having knife guideways in their sole engaging surfaces, sliding beds arranged for movement toward and away from one another, means for positioning a Louis heel in the machine, means controlled by the heel constructed and arranged to cooperate with the support and the crease plates for positioning the shoe in the machine in correlated arrangement with the heel, knives carried by the sliding beds and arranged to move in the

general direction of the length of the shoe for trimming surplus material from the marginal portions of the sole of the shoe to fit the heel-seat portion of the sole for the reception of the heel, said knives being inclined to the heel attaching face of the sole, the outer corners of the knives being arranged to travel in said knife guideways and the inner corners of the knives being raised substantially higher than the outer corners of the knives, shoulderng knives carried by the sliding beds and constructed and arranged to be moved transversely of the sole, both pairs of knives being arranged to be moved with the sliding beds and also constructed and arranged to be moved relatively to the sliding beds, means for forming upon the heel shoulders substantially complementary to the heel-breast-receiving shoulders formed on the sole, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.

74. A heel-seat fitting and heel trimming machine having, in combination, a shoe support, a machine frame, sliding beds mounted for movement toward and away from one another in the machine frame, crease plates constructed and arranged to enter the rand crease of a shoe on the support and having knife guideways in their sole engaging surfaces, a knife carried by each of the sliding beds and arranged to be moved lengthwise of the shoe, said knives being guided for reciprocation in said sliding beds and being positioned in the knife guideways of the crease plates, means for positioning a Louis heel in the machine, means controlled by the heel constructed and arranged to cooperate with the support and the crease plates for positioning the shoe in the machine in correlated arrangement with the heel, knives for forming heel-breast-receiving shoulders substantially at the heel breast line of the sole, knives for forming on the heel shoulders substantially complementary of the heel-breast-receiving shoulders formed on the sole, said means for locating the heel and the sole in correlated positions in the machine being constructed and arranged to insure that the shoulders formed upon the heel and the heel-breast-receiving shoulders formed on the sole are complementary to one another and are arranged to register with one another to facilitate the correct positioning of the heel upon the sole of the shoe, and means for operating the knives.

75. A heel-seat fitting and heel trimming machine having, in combination, a shoe support, crease plates constructed and arranged

to enter the rand crease of a shoe on the support, sliding beds arranged to be moved toward and away from one another transversely of the shoe, means for positioning a Louis heel in the machine, means controlled by the heel constructed and arranged to cooperate with the support and the crease plates for positioning the shoe in the machine in correlated arrangement with the heel, means for trimming the marginal portions of the sole of the shoe to fit the heel-seat portion of the sole for the reception of the heel, a shoulderng knife mounted for reciprocation along one of the sliding beds in a direction transversely of the length of the shoe, said knives being inclined to the heel attaching face of the sole and being disposed transversely of the sole, means for operating the knives relatively to the sliding beds and the shoe support, knives for forming on the heel shoulders substantially complementary to the heel-breast-receiving shoulders formed on the sole, said means for locating the heel and the sole in correlated positions in the machine being constructed and arranged to insure that the shoulders formed upon the heel and the heel-breast-receiving shoulders formed on the sole are complementary to one another and are arranged to register with one another to facilitate the correct positioning of the heel upon the sole of the shoe, and means for operating the knives.

76. A heel-seat fitting and heel trimming machine having, in combination, a shoe support, crease plates constructed and arranged to enter the rand crease of a shoe on the support, sliding beds arranged to be moved toward and away from each other transversely of the shoe, knives carried by the sliding beds and mounted for movement relatively therewith for trimming the marginal portions of the sole of the shoe, a knife carried by and mounted for reciprocation in each sliding bed transversely of the shoe for forming heel-breast-receiving shoulders upon the sole of the shoe, said shoulder forming knives being inclined to the attaching face of the sole and being disposed transversely of the sole, means for operating the knives relatively to the sliding beds and to the shoe support, means for initially setting the shoulderng knives in their proper positions relatively to the sliding beds, means for positioning a Louis heel in the machine, knives for forming on the heel shoulders substantially complementary to the heel-breast-receiving shoulders formed on the sole, mechanism controlled by said heel-positioning means for locating the sole in correlated position in the machine relatively to said heel to insure that the shoulders formed upon the heel and the heel-breast-receiving shoulders are complementary to one another and are arranged to register with one another to facilitate the correct posi-

tioning of the heel upon the sole of the shoe, and means for operating the knives.

77. A heel-seat fitting and heel trimming machine having, in combination, a shoe support, sliding beds arranged to be moved toward and away from one another transversely of the sole of a shoe on the support, a crease plate carried by each of the sliding beds and constructed and arranged to enter the rand crease of the shoe, means for positioning a Louis heel in the machine, means controlled by the heel constructed and arranged to cooperate with the support and the crease plates for positioning the shoe in the machine in correlated arrangement with the heel, a knife mounted for movement lengthwise of the shoe and carried by and guided for reciprocation in one of the sliding beds, said knife being inclined to the attaching face of the sole, a shouldering knife carried by each of the sliding beds and mounted for movement transversely of the shoe for forming heel-breast-receiving shoulders upon the sole, said shouldering knives being inclined to the attaching face of the sole, means for reciprocating the knives relatively to the sliding beds and to the shoe support, knives for forming on the heel shoulders substantially complementary to the heel-breast-receiving shoulders formed on the sole, said means for locating the heel and the sole in correlated positions in the machine being constructed and arranged to insure that the shoulders formed upon the heel and the heel-breast-receiving shoulders are complementary to one another and are arranged to register with one another to facilitate the correct positioning of the heel upon the sole of the shoe, and means for operating the knives.

78. A heel-seat fitting and heel trimming machine having, in combination, a shoe support, crease plates constructed and arranged to enter the rand crease of a shoe carried by the support, back gage mechanism for positioning the shoe to be trimmed lengthwise of the shoe relatively to the crease plates, a heel clamp constructed and arranged to receive a Louis heel and by its position to determine the position of the back gage, means for normally urging the back gage toward the shoe and for normally urging the heel clamp against the heel, means for normally locking the heel in the heel clamp and the back gage in its foremost position toward the shoe to prevent its movement away from the shoe, and means for trimming the heel in the heel clamp for reception by the shoe.

79. A heel-seat fitting and heel trimming machine having, in combination, a shoe support, crease plates constructed and arranged to enter the rand crease of a shoe carried by the support, back gage mechanism for positioning the shoe to be trimmed lengthwise of the shoe relatively to the crease plates, a heel clamp constructed and arranged to re-

ceive a Louis heel to be attached to the shoe and by its position to determine the position of the back gage, means for normally urging said heel clamp against the heel, means for normally locking the heel in the heel clamp positively to hold the heel in position in the machine and for locking the back gage to prevent its movement away from the shoe, means for trimming the heel in the heel clamp for reception by the shoe, and means controlled by the operator for unlocking the back gage to move the same away from the shoe and for releasing the heel from the heel clamp.

80. A heel-seat fitting and heel trimming machine having, in combination, a shoe support, a back gage for positioning a shoe upon the support in the machine in a direction lengthwise of the shoe, a heel clamp constructed and arranged to receive a Louis heel and to control the position of the back gage, said heel clamp including abutments for contacting with the rear portion of the heel and the breast of the heel and clamps constructed for movement with one of the aforesaid abutments and extending laterally of the heel to position the heel centrally with respect to said abutments, and means for trimming the heel in the heel clamp for reception by the shoe.

81. A heel-seat fitting and heel trimming machine having, in combination, a shoe support, a back gage for positioning a shoe lengthwise thereof upon the support, a heel clamp for controlling the position of the back gage, said heel clamp including abutments for contacting with the rear portion of a Louis heel and the breast of the heel and clamping members extending laterally of the heel and constructed and arranged to position the heel in its correct lateral position with respect to said abutments, compensating means whereby the clamping members and the abutments will normally engage the heel, and means for trimming the heel in the heel clamp for reception by the shoe.

82. A heel-seat fitting and heel trimming machine having, in combination, a shoe support, a back gage for positioning a shoe lengthwise upon the support, a heel clamp for controlling the position of the back gage, said heel clamp including abutments for contacting with the rear portion and the breast of a Louis heel and clamping members extending laterally of the heel and constructed and arranged to position the heel in its correct lateral position with respect to the aforesaid abutments, means for locking the heel in the heel clamp and for holding the back gage in its forward position against the shoe, means for trimming the heel in the heel clamp for reception by the shoe, and means for moving the back gage out of engagement with the shoe and the heel clamp out of engagement with the heel.

83. A heel-seat fitting and heel trimming

- machine having, in combination, a shoe support, a back gage for positioning a shoe lengthwise upon the support, a heel clamp for controlling the position of the back gage, said heel clamp including abutments for contacting with the rear portion and the breast of a Louis heel and having clamping members extending laterally of the heel and constructed and arranged to position the heel in its correct lateral position with respect to said abutments, means for locking the heel in the heel clamp and for holding the back gage in its forward position against the shoe, means for moving the back gage out of engagement with the shoe and the heel clamp out of engagement with the heel, means for trimming the heel in the heel clamp for reception by the shoe, and means for adjusting the heel clamp for receiving heels of different sizes.
84. A heel-seat fitting and heel trimming machine having, in combination, means for receiving a heel, means for receiving the sole of a shoe, means for trimming the heel in the heel receiving means to form shoulders on the heel, means for trimming the sole in the sole receiving means to form heel-breast-receiving shoulders on the sole, and mechanism controlled by the heel for correlating the positions of the sole in the sole receiving means and the heel in the heel receiving means relatively to their respective trimming means constructed and arranged to insure that the shoulders formed upon the heel are complemental to the heel-breast-receiving shoulders.
85. A heel-seat fitting and heel trimming machine having, in combination, means for receiving a heel, means for receiving the sole of a shoe, means for trimming the sole to provide a reduced heel-seat portion thereof and a pair of heel-breast-receiving shoulders upon the sole in the sole receiving means, trimming means for truncating a portion of the heel to form shoulders thereon, and mechanism controlled by the heel for correlating the positions of the sole in the sole receiving means and the heel in the heel receiving means relatively to their trimming means constructed and arranged to insure that the shoulders formed upon the heel will coincide with the heel-breast-receiving shoulders when the heel is correctly positioned upon the shoe.
86. A heel-seat fitting and heel trimming machine having, in combination, means for receiving a Louis heel, means for receiving a sole attached to a shoe, means for trimming the heel in the heel receiving means to form shoulders upon the heel, means for trimming the sole in the sole receiving means to form heel-breast-receiving shoulders on the sole, and mechanism controlled by the heel for correlating the positions of the sole in the sole receiving means and the heel in the heel receiving means.
87. A heel-seat fitting and heel trimming machine having, in combination, means for receiving a heel, means for receiving a sole attached to a shoe, knives for trimming the heel in the heel receiving means to form shoulders on the heel, knives for trimming the sole in the sole receiving means to form heel-breast-receiving shoulders on the sole, mechanism controlled by the heel for correlating the positions of the sole in the sole receiving means and the heel in the heel receiving means relatively to their respective knives constructed and arranged to insure that the shoulders formed upon the heel are complemental to the heel-breast-receiving shoulders, and means for operating the knives.
88. A heel-seat fitting and heel trimming machine having, in combination, means for receiving a Louis heel, means for receiving a sole attached to a shoe, knives for trimming the sole to provide a reduced heel-seat portion of the sole and a pair of heel-breast-receiving shoulders upon the sole in the sole receiving means, knives for truncating a portion of the heel to form shoulders thereon, mechanism controlled by the heel for correlating the positions of the sole in the sole receiving means and the heel in the heel receiving means relatively to their respective knives constructed and arranged to insure that the shoulders formed upon the heel will match with the heel-breast-receiving shoulders in order correctly to position the heel upon the shoe, and means for operating the knives.
89. A heel-seat fitting and heel trimming machine having, in combination, means for receiving a heel, means for receiving a sole attached to a shoe, knives for trimming the heel in the heel receiving means to form shoulders on the heel, knives for trimming the sole in the sole receiving means to form heel-breast-receiving shoulders on the sole, mechanism controlled by the heel for correlating the positions of the sole in the sole receiving means and the heel in the heel receiving means relatively to their respective knives constructed and arranged to insure that the shoulders formed upon the heel are complemental to the heel-breast-receiving shoulders, means for securing the correlating means against movement during the trimming operation, and means for operating the knives.
90. A heel-seat fitting and heel trimming machine having, in combination, means for receiving a Louis heel, means for receiving a sole attached to a shoe, knives for trimming the sole to provide a reduced heel-seat por-

tion of the sole and a pair of heel-breast-receiving shoulders upon the sole in the sole receiving means, knives for truncating a portion of the heel to form shoulders thereon, 5 mechanism controlled by the heel for correlating the positions of the sole in the sole receiving means and the heel in the heel receiving means relatively to their respective knives constructed and arranged to insure that the 10 shoulders formed upon the heel will match with the heel-breast-receiving shoulders in order correctly to position the heel upon the shoe, means for securing the correlating means against movement during the trimming operation, and means for operating the 15 knives.

91. A heel-seat fitting and heel trimming machine having, in combination, means for receiving a Louis heel, means for receiving the sole of a shoe, means for trimming the heel in the heel receiving means to form at the ends of the feather edge of the breast of the heel a pair of shoulders which extend rearwardly of the heel and toward the sides of the heel, means for trimming the sole in the sole receiving means to form heel-breast-receiving shoulders on the sole and mechanism controlled by the heel, for correlating the positions of the sole in the sole receiving means and the heel in the heel receiving means relatively to their respective trimming means constructed and arranged to insure that the shoulders formed upon the heel are complementary to the heel-breast-receiving shoulders.

92. A heel-seat fitting and heel trimming machine having, in combination, means for receiving a Louis heel, means for receiving a sole attached to a shoe, knives for trimming the sole to provide a reduced heel-seat portion of the sole and a pair of heel-breast-receiving shoulders on the sole in the sole receiving means, knives for forming at the ends of the feather edge of the breast of the heel a pair of shoulders which extend rearwardly of the heel and toward the sides of the heel, mechanism controlled by the heel for correlating the positions of the sole in the sole receiving means and the heel in the heel receiving means relatively to their respective knives constructed and arranged to insure that the shoulders formed upon the heel will match with the heel-breast-receiving shoulders in order correctly to position the heel upon the shoe, and means for operating the knives.

93. A heel-seat fitting and heel trimming machine having, in combination, means for receiving a heel, means for receiving the sole of a shoe, means for trimming the heel in the heel receiving means to form shoulders on the heel, means for receiving the sole in the sole receiving means to form heel-breast-receiving shoulders on the sole, and connections between the heel receiving means and the sole receiving mechanism controlled by

the heel for correlating the positions of the sole in the sole receiving means and the heel receiving means relatively to their respective trimming means constructed and arranged to insure that the shoulders formed upon the heel are complementary to the heel-breast-receiving shoulders.

94. A heel-seat fitting and heel-trimming machine having, in combination, means for receiving a Louis heel, means for receiving a sole attached to a shoe, knives for trimming the sole to provide a reduced heel-seat portion of the sole and a pair of heel-breast-receiving shoulders upon the sole in the sole receiving means, knives for truncating a portion of the heel to form shoulders thereon, connections between the heel receiving means and the sole receiving means for correlating the positions of the sole in the sole receiving means and the heel in the heel receiving means relatively to their respective knives constructed and arranged to insure that the shoulders formed upon the heel will match with the heel-breast-receiving shoulders in order correctly to position the heel upon the shoe, and means for operating the knives.

95. A heel-seat fitting and heel trimming machine having, in combination, means for receiving a Louis heel, means including a back gage for receiving a shoe, means for trimming the heel in the heel receiving means to form shoulders upon the heel, means for trimming the sole of the shoe in the shoe receiving means to form heel-breast-receiving shoulders on the sole, and connections between the heel receiving means and the back gage for correlating the positions of the sole lengthwise thereof in the sole receiving means and the heel in the heel receiving means relatively to their respective trimming means constructed and arranged to insure that the shoulders formed upon the heel will match with the heel-breast-receiving shoulders in order correctly to position the heel upon the shoe.

96. A heel-seat fitting and heel trimming machine having, in combination, means for receiving a Louis heel, means including a back gage for receiving a shoe, means for trimming the heel in the heel receiving means to form shoulders upon the heel, means for trimming the sole of the shoe in the sole receiving means to form heel-breast-receiving shoulders on the sole, and connections between the heel receiving means and the back gage for correlating the positions of the sole lengthwise thereof in the sole receiving means and the heel in the heel receiving means relatively to their respective trimming means constructed and arranged to insure that the shoulders formed upon the heel will match with the heel-breast-receiving shoulders in order correctly to position the heel upon the shoe. 115 120 125

97. A heel-seat fitting and heel trimming 139

machine having, in combination, means for receiving a Louis heel, means including a back gage for receiving a shoe, knives for trimming the sole of the shoe to provide a reduced heel-seat portion of the sole and a pair of heel-breast-receiving shoulders upon the sole of the shoe in the shoe receiving means, knives for truncating a portion of the heel to form shoulders thereon, and connections between the heel receiving means and the back gage for correlating the positions of the sole lengthwise thereof in the sole receiving means and the heel in the heel receiving means relatively to their respective knives constructed and arranged to insure that the shoulders formed upon the heel will coincide with the heel-breast-receiving shoulders when the heel is correctly positioned upon the shoe.

98. A heel-seat fitting and heel trimming machine having, in combination, means for receiving a Louis heel, means including a back gage for receiving a shoe, knives for trimming the sole to provide a reduced heel-seat portion of the sole of the shoe and a pair of heel-breast-receiving shoulders upon the sole in the shoe receiving means, knives for truncating a portion of the heel to form shoulders thereon, connections between the heel receiving means and the back gage for correlating the positions of the sole lengthwise thereof in the sole receiving means and the heel in the heel receiving means relatively to their respective knives constructed and arranged to insure that the shoulders formed upon the heel will match with the heel-breast-receiving shoulders in order correctly to position the heel upon the shoe, means for securing the heel receiving means and the back gage against movement during the trimming operation, and means for operating the knives.

99. A heel-seat fitting and heel trimming machine having, in combination, means for receiving a Louis heel, means including a back gage for receiving a shoe, knives for trimming the sole to provide a reduced heel-seat portion of the sole of the shoe and a pair of heel-breast-receiving shoulders upon the sole in the sole receiving means, knives for truncating portions of the heel to form at the ends of the feather edge of the breast of the heel a pair of shoulders which extend rearwardly of the heel and toward the sides of the heel, connections between the heel receiving means and the back gage for correlating the positions of the sole lengthwise thereof in the sole receiving means and the heel in the heel receiving means relatively to their respective knives constructed and arranged to insure that the shoulders formed upon the heel will match with the heel-breast-receiving shoulders in order correctly to position the heel upon the shoe, and means for operating the knives.

100. A heel-seat fitting and heel trimming machine having, in combination, means for receiving a heel, cutters for truncating a portion of the heel to form shoulders thereon, jaws constructed and arranged to enter the rand crease of a shoe prior to the attaching of a heel to the shoe, means for opening and closing the jaws, cutters constructed and arranged for relative movement with the jaws during the opening and closing of the jaws, means for moving the cutters relatively to the jaws to form heel-breast-receiving shoulders upon the sole of the shoe, and mechanism controlled by a heel in the heel receiving means for correlating the position of the heel in the heel receiving means and for positioning the sole relatively to said last-named cutters to insure that the shoulders formed upon the heel are complementary to the heel-breast-receiving shoulders.

101. A heel-seat fitting and heel trimming machine having, in combination, means for receiving a heel, cutters for truncating a portion of the heel to form shoulders thereon, crease plates constructed and arranged for positioning in the rand crease of the shoe at opposite sides of the shoe, one of said crease plates being mounted for movement toward a crease plate arranged to be positioned in the rand crease at the opposite side of the shoe, a knife carried by each of the crease plates, each of said knives being mounted for movement relatively to the crease plates, means for causing relative movement between the crease plates and the knives simultaneously to form heel-breast-receiving shoulders upon the sole, and mechanism controlled by a heel in the heel receiving means for correlating the positions of the heel in the heel receiving means and for positioning the sole relatively to said cutters to insure that the shoulders formed upon the heel will coincide with the heel-breast-receiving shoulders when the heel is correctly positioned upon the sole.

102. A heel-seat fitting and heel trimming machine having, in combination, means for receiving a heel, cutters for truncating portions of the heel to form shoulders thereon, a pair of crease plates constructed and arranged to be received in the rand crease of a shoe to support the marginal portions of the sole of the shoe from the breast line of the sole rearwardly of the sole, a pair of knives constructed and arranged to engage the forward edges of the crease plates and with the crease plates to constitute shear couples for forming transverse cuts in the sole at its heel breast line, thereby forming heel-breast-receiving shoulders upon the sole, and mechanism controlled by the heel in the heel positioning means for correlating the position of the heel in the heel receiving means and the sole relatively to said knives to insure that the shoulders formed upon the heel will engage with the heel-breast-receiving shoulders.

in order accurately to position the heel upon the shoe.

103. A heel-seat fitting and heel trimming machine having, in combination, means for receiving a heel, cutters for trimming portions of the heel to form shoulders thereon, a pair of sole supporting plates arranged to be introduced between the heel-seat portion of the sole of a shoe and the lasted-in margin of the counter portion of the shoe upper to which the sole is attached, means for moving said plates toward and away from each other, a gage for determining the position of the sole lengthwise thereof upon the plates, a pair of knives carried by and movable relatively to the plates, said knives being constructed and arranged to form heel-breast-receiving shoulders upon the sole, and mechanism controlled by the heel in the heel positioning means for locating the gage in order to insure that the shoulders formed upon the heel will coincide with the heel-breast-receiving shoulders when the heel is correctly positioned upon the shoe.

25 In testimony whereof we have signed our names to this specification.

GEORGE HAZELTON.
FRED RICKS.

in order accurately to position the heel upon the shoe.

103. A heel-seat fitting and heel trimming machine having, in combination, means for receiving a heel, cutters for trimming portions of the heel to form shoulders thereon, a pair of sole supporting plates arranged to be introduced between the heel-seat portion of the sole of a shoe and the lasted-in margin of the counter portion of the shoe upper to which the sole is attached, means for moving said plates toward and away from each other, a gage for determining the position of the sole lengthwise thereof upon the plates, a pair 15 of knives carried by and movable relatively to the plates, said knives being constructed and arranged to form heel-breast-receiving shoulders upon the sole, and mechanism controlled by the heel in the heel positioning means for locating the gage in order to insure that the shoulders formed upon the heel will coincide with the heel-breast-receiving shoulders when the heel is correctly positioned upon the shoe.

25 In testimony whereof we have signed our names to this specification.

GEORGE HAZELTON.
FRED RICKS.

CERTIFICATE OF CORRECTION.

Patent No. 1,847,244.

March 1, 1932.

GEORGE HAZELTON ET AL.

It is hereby certified that error appears in the printed specification of the above numbered patent requiring correction as follows: Page 23, line 67, claim 93, after "and" insert the words "the heel in"; and that the said Letters Patent should be read with this correction therein that the same may conform to the record of the case in the Patent Office.

Signed and sealed this 17th day of January, A. D. 1933.

M. J. Moore,
Acting Commissioner of Patents.
